UNITED STATES PATENT OFFICE.

GEORGE AINSWORTH, OF GREAT NECK, NEW YORK, ASSIGNOR TO ALFRED VESTER & SONS, INC., OF PROVIDENCE, RHODE ISLAND, A CORPORATION OF RHODE ISLAND.

DESIGN FOR A COMBINED HUSK AND SOCKET COVER.

Application filed April 23, 1923. Serial No. 5,916. Term of patent 14 years.

To all whom it may concern:

Be it known that I, GEORGE AINSWORTH, a citizen of the United States, and residing at Great Neck, in the county of Nassau and State of New York, have invented a new, original, and ornamental Design for a Combined Husk and Socket Cover, of which the following is a specification, reference being had to the accompanying drawing, forming part thereof.

Figure 1 is a perspective view of a combined husk and socket cover, showing my new design.

Figure 2 is a bottom plan view of my husk and socket cover.

I claim—

The ornamental design for a combined husk and socket cover, as shown.

GEORGE AINSWORTH.
